N. Y., a corporation of Maryland

Original application September 20, 1935, Serial
No. 41,489, now Patent No. 2,139,434, dated De-
cember 6, 1938. Divided and this application
March 30, 1938, Serial No. 199,011

12 Claims. (Cl. 105—197.1)

This invention has been divided from my co-pending application Serial No. 41,489, filed September 20, 1935, for Railway trucks and matured as Patent Number 2,139,434 on December 6, 1938.

5 This invention relates to railway trucks and more particularly to the construction of the side frames, spring nests and spring plates thereof.

An object of the present invention, generally considered, is the improvement in railway trucks 10 and particularly the construction of the side frames, spring nests and spring plates, whereby increased strength of the frame and increased capacity of the bolster springs are secured, provision being made for the assembly and removal

15 of nests of bolster springs with respect to the associated side frames while said nests are assembled as units between associated spring plates.

Another object of the instant invention is to provide a railway truck of relatively short wheel 20 base using bolster spring groups generally of modified H-shape in plan to obtain increased spring capacity while avoiding interference between the springs and associated brake rigging.

A further object of the invention is to provide 25 a railway truck with the associated parts so constructed that interference between the inside hung brake beams and the inner bolster spring support is avoided by decreasing the longitudinal dimension of the inner line of springs.

30 An additional object of the invention is the arrangement of spring nests and the construction of the plates for said nests, whereby said nests may be applied to and removed from the associated side frame as units.

35 Other objects and advantages of the invention relating to the particular arrangement and construction of the various parts will become apparent from the following description.

40 Referring now to the drawings which illustrate exemplary forms of the invention:

Figure 1 is a fragmentary side elevation of a 45 railway truck embodying a form of the present invention, portions of the side frame, bolster, spring nest and spring plate being shown in vertical section to more clearly illustrate the invention.

Figure 2 is a partial fragmentary plan and 50 partial fragmentary horizontal sectional view of the railway truck disclosed by Figure 1, the sectional portion being taken along the lines 2—2 of Figure 1 looking in the direction of the arrows.

Figure 3 is a horizontal sectional view taken 55 through the bolster guiding portions of the columns, otherwise corresponding approximately

with the right-hand portion of Figure 2 but showing another embodiment of the invention.

Figure 4 is a fragmentary sectional view taken along the lines 4—4 of Figure 3 and looking in the direction of the arrows.

Figure 5 is a plan view of another nest of 10 springs embodying the present invention, a portion thereof being shown in horizontal section and the upper spring plates being removed so as to more clearly illustrate the invention.

Figure 6 is a side elevational view of the spring 15 nest disclosed by Figure 5 with the right-hand rear spring unit removed.

Referring now to the drawings in detail, like 20 parts being designated by like reference characters, and first considering the embodiment of the invention illustrated in Figures 1 and 2, there is shown a portion of a railway truck having laterally spaced side frames 1^a, only the intermediate portion of one of which is illustrated. Each side frame 1^a desirably comprises a compression member 2^a, a tension member 3^a and bolster guide columns or strut portions 4^a, the latter of which space intermediate portions of the compression and tension members to leave a bolster or window 25 opening 5^a therebetween. The compression and tension members extend outwardly beyond the guide columns 4^a where they merge adjacent each end of the side frame with one another and join with integrally formed journal boxes (not shown) 30 or, in contradistinction thereto, form jaws for removable or separable journal boxes.

In the present embodiment of the invention the truck illustrated is one of relatively short wheel base, and in such a structure, as will be 35 understood, the brake hanger brackets (not shown), which extend inwardly of the railway truck from the guide columns, are spaced very close relative to one another. The tension member 3^a between the guide columns is generally 40 box-shaped in cross section and comprises an upper web 7^a forming a spring seat, a lower web 8^a spaced vertically from the upper web 7^a, and laterally spaced vertically disposed side webs or flanges 9^a. For rigidifying and strengthening the 45 side frame and particularly the tension member and the junction between the tension member and guide columns the tension member is upwardly convoluted or embossed, preferably along the longitudinal center line of the frame adjacent 50 the junctions with the bolster guide columns, to form upper diagonally disposed web portions 11^a which start or are formed near the center of the spring seat portion and therefrom extend diagonally upward through the guide columns to 55

ward the ends of the side frame. In order to have the reinforcements 11^a extend from near the center of the spring seat to the guide columns without occupying or closing up too much of the clear window opening space, the reinforcements preferably extend to the guide columns on a moderate inclination, and after intersecting or union with the guide columns they are thence continued upwardly and outwardly at a much greater inclination to correspond more closely with the relatively steep inclination of the main inclined end portions 12^a of the tension member. In this respect the side frames differ somewhat from the construction of the side frame described and claimed in my prior Patent No. 1,652,808 of December 13, 1927.

The reinforcing construction heretofore described results in a bifurcation of the upper web of the tension member, thereby producing a triangular or inclined reinforcement at the junction between the tension member and bolster guide columns, and, in addition, forms embossments with which a spring plate is adapted to engage thereby obviating the necessity of the usual squaring lugs or the provision of squaring means in addition to said lugs for retaining the spring nest in a predetermined position. In order to provide an adequate spring-supporting area, the upper web 7^a between the bolster guide columns is laterally widened in both directions beyond the webs or flanges 9^a , as indicated at 17^a and 18^a respectively. These extensions 17^a and 18^a are desirably braced with respect to the webs 9^a by triangular gussets 19^a . The side frames 1^a are desirably connected together by means of the usual bolster 13^a which has an end portion thereof extending into and occupying the upper area of the bolster opening 5^a . The bolster end is desirably provided with laterally spaced lugs 14^a which extend outwardly from the sides of the bolster and engage or embrace the guide columns 4^a and a lower spring group engaging surface 14^b .

In the present embodiment the railway truck is of the spring-plankless type and is provided with a nest of springs 28^a , forming a resilient mounting for the bolster end, and is interposed between the tension member 3^a and the associated end of the bolster. The nest of springs 28^a has a lower spring plate 25^a which bears directly on the upper web 7^a of the tension member. The lower spring plate 25^a is desirably upwardly embossed or corrugated, as indicated at 29^a , to nest over the corrugations or embossments 11^a on the associated side frame, thereby retaining the spring plate and the associated nest of springs in a desired or predetermined position. The lower spring plate 25^a has upwardly extending collars or annular flanges 26^a which serve to position or center the associated springs or spring units 28^a of the nest.

The nest of springs is also provided with an upper spring plate 35^a , preferably corresponding with the lower spring plate 25^a , and both of said plates are desirably retained in assembled relation by a normally vertical bolt 42 . The head 42^a of the bolt is preferably received in an upwardly embossed portion forming a downwardly opening pocket 43 in the lower spring plate 25^a , and the associated nut 44 on the free or upper end of the said bolt is received in a correspondingly upwardly opening pocket or downwardly embossed portion 45 formed in the upper spring plate 35^a .

In order to provide a nest of springs with de-

sirable stability against rocking of the supported bolster 13^a illustrated as of the type described and claimed in my copending application Serial No. 183,209, filed January 3, 1938, while at the same time making it possible to insert and remove the spring nest 28^a as a unit after assembly between the upper and lower spring plates, the outer spring units or coils are desirably positioned a normal distance apart whereby they are disposed with their upper portions longitudinally beyond the planes of the bolster guiding surfaces. The innermost spring units, however, are positioned close enough together so that they clear the bolster guiding surfaces, and the inner portions of the plates 25^a and 35^a are formed of correspondingly reduced width, as most clearly illustrated in Figure 2, so that the outline of the springs inwardly of the outermost row thereof is shorter than the distance between the guide column portions, thereby permitting insertion of the entire nest of springs after assembly with the plates into position with respect to the associated side frame. The innermost spring units are also closely associated as illustrated and described so as to prevent interference between these springs and the inside hung brake beams, the latter of which are not shown.

It has not previously been possible to make such an assembly of the entire group of springs when employing a double truss side frame of the type illustrated because the basic group is fundamentally H-shaped in plan and the window opening below the column faces or bolster guiding portions is too narrow to accommodate springs in position, especially when the plate is raised to clear the triangular portions 11^a of the inner truss. By keeping all but the outer row of springs within the distance between the transverse vertical planes of the bolster engaging surfaces of the guide columns the spring group may be raised to clear the inner truss or embossments 11^a and allow for its application or removal as a unit.

It will be observed that the nest of springs 28^a and the associated upper and lower spring plates 35^a and 25^a , respectively, are formed substantially or generally H-shape in plan, including five springs two of which form the inner upright of the H, and are positioned close enough together so that these springs and their associated portions of the spring plate may be sufficiently narrow to pass between the bolster guiding surfaces of the guide columns in order to allow for application and removal of the nest while assembled with the plates. The springs, two in number, forming the outer upright of the H are positioned far enough apart to provide for the desired nest stability against rocking of the superimposed bolster so that the outer width of the nest is greater than the distance between the transverse vertical planes of the bolster guiding surfaces of the guide columns. Completing the spring nest is a single spring positioned on the cross piece of the H, the axis of which lies substantially in the longitudinal vertical plane of the side frame.

Referring now to the embodiment of the invention illustrated in Figures 3 and 4, there is shown a fragmentary portion of a side frame 1^b having a tension member 3^b on which is supported a nest of springs 28^b . As in the preceding embodiment, the nest of springs has a lower spring plate 25^b which is upwardly embossed or corrugated, as indicated at 29^b , to nest over the corrugations or embossments 11^b on the tension member 3^b of

the associated side frame, thereby retaining the nest in a predetermined position on the tension member. The lower spring plate 25^b has upwardly extending collars or annular flanges 26^b which serve to position or center the associated springs or spring units of the nest. Each spring unit in the present embodiment comprises an outer coil 46 and an inner coil 47 rather than being merely of the single coil type as in the preceding embodiment. It will, however, be understood that the present invention need not be limited to the types of spring units employed in this or other embodiments.

The nest of springs 28^b is also desirably provided with an upper spring plate (not shown) preferably corresponding with the lower spring plate 25^b, said plates being desirably held together by a normally vertical bolt 42^b and an associated nut (not shown) substantially the same as in the preceding embodiment. On account of the fact that the present embodiment has seven spring units, rather than five as in the preceding embodiment, only five of the said units are desirably disposed between the main upper and lower spring plates, three of said units being disposed outwardly of the longitudinal central plane of the associated side frame 1^b, one unit being disposed with its axis in said plane, and the remaining unit being disposed inwardly of said plane. The spring plates, as in the preceding embodiment, are formed sufficiently narrow inwardly of the outer row of springs so that the associated nest, when assembled with said plates, may be applied to and removed from the associated frame as an assembled unit.

Supplementing the springs 46 and 47 of the nest of springs 28^b are auxiliary spring units 48, each unit desirably comprising an outer coil 48 and an inner coil 50 and having an auxiliary lower plate 51 and an upper reversely formed complementary spring plate (not shown). The main lower spring plate 25^b is interlocked with the lower auxiliary spring plates 51 in any desirable manner, for example, by having the adjacent portions 52 and 53 of each auxiliary spring plate upwardly flanged or directed inwardly of the spring nest, as most clearly illustrated in Figure 4, and received in correspondingly formed pockets 54 and 55 formed on said main spring plate 25^b.

The interlocking or inter-engagement between the upper main and auxiliary spring plates may correspond substantially with that structure disclosed and described for the interlocking between the lower main and auxiliary spring plates as will be understood, said upper and lower main spring plates being desirably interchangeable and of substantially identical construction, and the auxiliary spring plates, being symmetrical about the longitudinal vertical plane of the rear row of springs, are also interchangeable.

In assembling the nest of springs illustrated in Figures 3 and 4 the main nest 28^b may be assembled with the main upper and lower spring plates and the entire unit secured together by means of the bolt 42^b prior to insertion in the window opening 5^b of the side frame 1^b. The lower auxiliary spring plates 51 being in place, the nest 28^b is elevated sufficiently to clear the triangular reinforcing portions 11^b of the side frame 1^b and then lowered down over the flanges 52 and 53 of the lower auxiliary spring plates 51 so that the interlock between said flanges and the pocketed portions 54 and 55 of the lower main spring plate 25^b is effected. After this procedure the auxiliary spring units 48 are applied or positioned over

the spring plates 51 around the spring positioning collars 56 thereon, and the top auxiliary plates (not shown) are then positioned over the spring units 48 with their corresponding flanges 52 and 53 fitting or projecting within the upwardly opening pockets 54 and 55 of the upper main spring plate (not shown).

Referring now to the embodiment of the invention illustrated in Figures 5 and 6, there is shown a nest of springs 28^c adapted to be employed like the nests 28^a and 28^b of the preceding embodiments, except that it involves an elliptic or banded leaf spring 57 in addition to the helical springs or spring units 58. Although the associated side frame is not illustrated, it will be clearly understood that the spring nest may be employed with the side frame like the nest of the springs 28^a and 28^b.

As in the preceding embodiment, the nest 28^c comprises main lower and upper spring plates 25^c and 35^c desirably held together by a pair of normally vertical bolts 42^c, the head of each bolt being preferably received in an upwardly or inwardly embossed portion forming a downwardly opening pocket 43^c in the lower main spring plate 25^c, and the associated nut 44^c on the upper or free end of each bolt being received in correspondingly upwardly opening pocket 45^c, the latter of which is formed by downwardly embossing the main upper spring plate 35^c.

These main plates 25^c and 35^c, when secured together by the bolts 42^c, secure the two outer helical spring units and the intermediate elliptic spring in assembled relation so that the nest 28^c may be handled as a unit for application and removal with respect to an associated side frame (not shown). As in each of the preceding embodiments, each spring plate 25^c and 35^c desirably has cylindrical spring positioning collars 26^c for the helical or coil springs and, in addition thereto, has a generally rectangular spring positioning collar 59 for the corresponding spring band 60 of the elliptic spring 57. Each collar 59 has relatively low sides 61 which allow the leaves of the elliptic spring to pass thereover. The low sides 61 are desirably joined by relatively high side or flange portions 62 which extend upwardly along the edges of the leaves and embrace those portions of the bands 60 laterally of the leaves.

Supplementing the springs of the nest of springs 28^c are auxiliary spring units 48^c, each unit in the present embodiment comprising a single coil, although double coils may be employed if desired, as in the preceding embodiment, not only for the auxiliary helical springs but also for the main helical springs. The spring units 48^c have associated therewith a lower auxiliary spring plate 51^c and an upper spring plate 63, said upper and lower spring plates being desirably formed identical so that they may be interchanged. The lowermost spring plate 25^c is interlocked with the lower auxiliary spring plate 51^c in any desired manner, for example, by having the adjacent portions 52^c and 53^c of said auxiliary spring plate upwardly flanged, as illustrated, and received in or extending into correspondingly formed pockets 54^c and 55^c on said main plate 25^c. The interlocking between the upper main and auxiliary spring plates may correspond substantially with that between the lower main and auxiliary spring plates, as will be understood. In assembling the nest of springs illustrated in Figures 5 and 6, the main nest 28^c or the elliptic spring 57 and the springs or spring units 58 may be assembled with the main upper and lower

- spring plates and the entire unit secured together by the bolts 42^c prior to insertion of the unit in the window opening of an associated side frame (not shown). The lower auxiliary spring plate 51^c, being previously set in place on a tension member of a side frame, the assembled nest 28^c is then inserted in a manner similar to the nest 28^b of the preceding embodiment, that is, it may be elevated if necessary to clear triangular reinforcing portions in the window of a side frame if employed with that particular type of side frame, and in any event raised sufficiently to clear the flange portions 52^c and 53^c on the auxiliary plate 51^c. The assembled nest is then lowered down over said flanges so as to effect the desired interlock between the main and auxiliary plates, said flange portions being received or positioned in the pockets 54^c and 55^c provided in the main spring plate.
- 20 The main spring plates 25^c and 35^c are shown with flat outer or frame and bolster engaging surfaces adapting them for employment with the conventional type of frame without triangular reinforcing portions like those designated by the reference character 11^a in Figures 1 and 2. If employed with a frame of the double truss type, such as described and claimed in my Patent No. 1,652,808 previously referred to, with such triangular reinforcing portions, it will be found desirable to have the plates corrugated like those of the preceding embodiments in order to nest with the reinforcements and thereby form means to retain the assembled unit in a predetermined position within the window opening of an associated side frame. After this procedure the auxiliary spring units 48^c are applied over the spring plates 51^c and around the spring positioning collars 56^c thereon and the top auxiliary spring plate 63 positioned over the spring units 48^c with its corresponding flanges 64 fitting within or extending into upwardly opening pockets 65 of the upper main spring plate 35^c.
- It will be understood that although I have shown only one side frame and the associated end of the bolster, the truck, as is usual, is formed with two side frames which are connected by means of the usual bolster or load-carrying member.
- I claim:
- 50 1. In a railway truck, in combination, a side frame comprising compression and tension members spaced at intermediate portions by bolster guide columns leaving a window opening therebetween, that portion of the tension member beneath said window opening being adapted to support a spring plate, and a nest of springs comprising upper and lower spring plates supported on said tension member, each spring plate having its outer end relatively wide to accommodate springs spaced apart such a distance that when assembled they will provide the nest with the desired stability against rocking of a supported bolster, which distance gives the nest an outer width greater than that between guide surfaces of said columns, and decreased in width toward its inner end to a distance less than that between said guide surfaces, whereby said nest of springs may be assembled with its plates and then inserted or removed as a unit.
- 70 2. In combination, a bolster with its ends formed with lower spring engaging surfaces, nests of springs with spring plates disposed in engagement with said surfaces, said plates being sufficiently wide at their outer ends so that the outer springs of the nests may be positioned far enough

apart to provide the nest with the desired stability against rocking of said bolster, and thus wider at said outer ends than the distance between the bolster guiding surfaces of associated side frames, and decreasing in width at the portions normally received in said side frame bolster openings in order to provide for application and removal of said nests of springs while said springs are assembled therewith.

3. A nest of at least five bolster spring units provided with associated spring plates for holding said units assembled, said plates being of maximum width at their outer ends, so that the outer spring units may be positioned far enough apart to provide the nest with the desired stability against rocking of an associated bolster and thus so far apart that the outer dimensions thereof are greater than the distance between the bolster guiding surfaces of an associated side frame, said plates being of lesser width inwardly therefrom to make application and removal with respect to said side frame possible while the spring units are assembled with respect thereto.

4. In a railway truck, in combination, a side frame comprising a compression member, a tension member, bolster guide columns spacing intermediate portions of said members and spaced to leave a bolster opening therebetween, that portion of the tension member beneath said bolster opening having embossments extending from the lower ends of the bolster guide columns toward the central portion thereof, a spring plate supported on said tension member and formed of corrugations interlocking with said embossments, a nest of springs supported on said spring plate and comprising a plurality of springs on each side of, and with their axes in planes disposed generally parallel to, the longitudinal central plane of said frame, said springs on the inner side of said plane being positioned close enough together to pass between the guide columns while assembled with the plate, and those on the outer side of said plane being positioned a distance apart sufficient to provide the nest with the desired stability against rocking of a supported bolster, which distance gives the nest an outer width greater than that between the guiding portions of the columns, and an upper plate of corresponding form disposed on top of said nest of springs and adapted to be engaged by the supported bolster.

5. A nest of at least five bolster spring units provided with associated members for holding said units assembled and formed as two rows with a central spring unit positioned directly between the rows, making an arrangement substantially H-shape in plan, the spring units of the outer row being positioned far enough apart to provide the nest with the desired stability against rocking of an associated bolster, and thus further apart than the distance between the bolster guiding surfaces of an associated side frame, the spring units of the inner row being positioned closer together than those of the outer row so as to be adapted, without disassembly, to pass between said bolster guiding surfaces.

6. A spring plate for a nest of springs generally H-shaped in plan, said plate being provided with at least five spring positioning collars corresponding with the springs on the uprights and the cross piece of said H, the collars for the springs on the inner upright of said H being positioned close enough together so that the width of the plate may be sufficiently narrow at that point to pass between the bolster guiding surfaces of an

associated side frame, thereby allowing for application and removal of the nest employing said plate while assembled, the collars for said springs, which are positioned farthest from one another 5 to form the ends of the outer upright of said H, being positioned far enough apart to provide for the desired nest stability against rocking of an associated bolster so that the outer width of the nest is greater than the distance between the 10 bolster guiding surfaces of said associated side frame.

7. A two-piece spring plate device adapted to engage one end of a nest of springs comprising a main spring plate engaging most of the springs 15 of said nest, and an auxiliary spring plate engaging at least one of the remainder of said springs, one of said plates having an angularly disposed flange directed inwardly of said nest and the other plate having a corresponding pocket normally receiving said flange and holding said plates in proper relation with respect to one another.

8. A two-piece spring plate device adapted to engage a nest of springs comprising a main spring plate engaging some of the springs of the nest, 20 and an auxiliary spring plate engaging at least one of the remainder of the springs, said main spring plate having a pocket facing away from said springs adapted to receive an angularly disposed flange provided on said auxiliary spring 25 plate for holding said plates in proper relation with respect to one another.

9. A nest of bolster spring units provided with associated spring plates for holding said units assembled, said plates being of maximum width at 30 their outer ends and of lesser width inwardly therefrom to facilitate application and removal with respect to an associated side frame while the spring units are in position with respect thereto, auxiliary springs and associated plates assembled 35 with said nest of springs, and means detachably interlocking said nest plates and auxiliary plates.

10. A nest of bolster spring units provided with associated spring plates, means connecting said plates for holding said nest assembled, said plates 40 being of maximum width at one end thereof so

that the associated springs may be positioned far enough apart to provide the nest with the desired stability against rocking of an associated bolster, and thus so far apart that the outer dimension thereof is greater than the distance between the guiding surfaces of an associated side frame, said plates being of lesser width at the other end thereof to make application and removal with respect to said side frame possible while the spring units are assembled with respect 10 thereto.

11. A nest of bolster spring units provided with associated main spring plates, means connecting said main spring plates for holding said units assembled, said plates being of maximum width 15 at one end thereof so that the associated springs may be positioned to provide the nest with the desired stability against rocking of an associated bolster, and thus so that the over-all dimension thereof is greater than the distance between the 20 guiding surfaces of an associated side frame, said main plates being of lesser width at the other end thereof to make application and removal with respect to said side frame possible while the spring units are assembled with respect thereto, and an 25 auxiliary spring plate engaging at least one other spring unit, said main and auxiliary spring plates having interlocking portions for maintaining the springs in a predetermined position.

12. A multi-part spring plate device adapted 30 to engage a nest of springs comprising a main spring plate engaging some of the springs of said nest, and an auxiliary spring plate engaging at least one of the remainder of said springs, one of 35 said plates having an angularly disposed flange and the other of said plates having a corresponding pocket normally receiving said flange so as to retain said plates in proper relation with respect to one another, one of said plates also having convoluted portions for interlocking engagement 40 with correspondingly formed portions of an associated side frame for holding said plates in proper relation with respect to the said side frame.

DONALD S. BARROWS. 45
